UNITED STATES PATENT OFFICE.

HAROLD M. BRAYTON, OF DOVER, NEW JERSEY.

COMBINATION INSTANTANEOUS AND DELAY FUSE.

Application filed July 11, 1924. Serial No. 725,437.

(GRANTED UNDER THE PROVISIONS OF THE ACT OF MARCH 3, 1883, 22 STAT. L., 625.)

The invention described herein, may be manufactured and used by or for the Government for governmental purposes without the payment to me of any royalty thereon.

5 The subject of this invention is a combination instantaneous and delay fuse.

In firing shells from artillery weapons or in dropping bombs from aircraft, it is desirable to provide a fuse for the shell which 10 may be set to give either instantaneous or delay action on impact. Further, there are certain conditions especially met with in artillery firing where an automatic selective delay action will function dependably.

15 These conditions substantially are in low angle firing where a graze or ricochet action is obtained and in high angle firing where the angle of fall is sufficient to provide a penetrating instead of a ricochet action. In 20 my improved fuse the instant of functioning depends upon the amount and length of resistance encountered.

During the ricochet action, the shell rarely plows the ground to a depth of more 25 than a few inches or a length of more than a few feet, the resistance offered being consequently small. Under these conditions the delay mechanism will function quickly but the time required for the movement of the 30 various elements will permit the shell to be out of the ground probably from three to five feet before the burst. For effective use against troops this is the ideal position sought for in the burst of a high explosive 35 shell.

In high angle impact where penetration is desired the resistance encountered being considerable, the delay action will be accordingly greater. By varying the weight or strength 40 of the inertia elements the actual amount of penetration before burst can be nicely regulated.

My invention, therefore, resides in providing a striker rod which may be selectively positioned in operative position to actuate a firing pin when it is desired to secure instantaneous action or which may be maintained in inoperative position when desired to employ delay action; and in establishing delay 50 elements, constituting an automatic selective mechanism for actuating the same firing pin whose instant of functioning depends upon the amount and the length of resistance encountered.

55 The principles embodied in obtaining the

foregoing results are equally applicable to fuses for artillery shells and aerial bombs.

To these and other ends, my invention consists in the construction, arrangement, and combination of elements, described hereinafter and pointed out in the claims forming a part of this specification.

A practical embodiment of my invention applied to an artillery point detonating fuse is illustrated in the accompanying drawings, 65 in which,

Fig. 1 is a longitudinal sectional view taken through a fuse and showing the device set for instantaneous action and in unarmed position.

70 Fig. 2 is a sectional view taken on the line 2—2 of Fig. 1, showing a detonating element in unarmed position, and

Fig. 3 is a similar view showing the detonating element in armed position.

75 Referring to the drawings by numerals of reference:

The fuse comprises a body 10, adapted for attachment to a projectile, in threaded engagement with a fuse head 11 and held 80 against rotation by a screw 12.

The body 10 carries a booster charge 13 packed in a booster chamber formed concentric with the fuse body and communicating with an eccentric bore 14, in which is disposed an approximately T-shaped rotor 15. The eccentric bore 14 may be in communication with an eccentric bore 16 which is provided for the purpose of properly counter-balancing the fuse. Since the 85 structure and operation of the rotor forms no part of the present invention it will be but briefly described herein.

The rotor is normally held in unarmed position, as shown in Figure 2, by means 90 of pins 17 until the rotation of the shell is sufficient to displace them through centrifugal force when the rotor rotates on its axis under the action of centrifugal force until it engages a stop 18, at which time a locking pin 19 carried by the rotor and adapted to be thrown out by centrifugal force, will be positioned in a recess 20 of the fuse body. During this rotation a blind cavity 21 moves off center to enable a detonating element 22 100 disposed in a cavity 22' to take its place in line with the firing pin.

105 Disposed within the body 10 and held in place by the head 11 is a plate 23 provided with a central aperture 24 and adapted to 110

support the various elements of the delay mechanism which are enclosed in a cavity 11' in the head 11 in rear of its apertured diaphragm 25.

5 The delay mechanism comprises a hollow plunger 26 and a sleeve 27 within the plunger and extending the entire length of the cavity 11'. The plunger 26 is formed with an internal annular rib 28 normally 10 positioned to close aperture 29 in the sleeve 27 and maintained in this position against an annular ring 30 by centrifugal pins 31. The ring 30 embracing the sleeve 27 insures proper alignment of the firing mechanism 15 and detonator and also serves to steady the sleeve 27 when the plunger moves forwardly upon impact of the projectile against the tension of a spring 32, which is confined by the diaphragm 25 and rib 28. Rotation 20 of the projectile throws out the centrifugal pins 31 leaving only the spring 32 to maintain the plunger in unarmed position during flight. When in the forward position, the rib 28 uncovers the aperture 29 to release balls 25 33 partially disposed in the aperture 29 from engagement with a guide 34 in the form of a cup either through the action of centrifugal force when the device is used in a shell or when used in a bomb through the 30 action of a spring 35 carried within the guide and abutting against the diaphragm 25 of the fuse body 11.

Extending through the base of the guide 35 34 is a firing pin holder, its stem 36 projecting a short distance within the guide and having an enlarged head 37 formed thereon normally abutting the rear face of the guide and carrying a firing pin 38. If desired, these elements may be integrally 40 constructed. Confined between the enlarged head 37 and the plate 23 is a spring 39 of less strength than the spring 35 within the guide 34 and adapted to return the firing pin and holder to forward position after 45 they have been set back on discharge and to retain them in this position during flight.

It will be noted that when the delay mechanism is in unarmed position as shown in Figure 1, the firing pin is held from the 50 detonator when disposed axially of the fuse during flight, by the spring 39 while the stronger spring 35 is prevented by the balls 33 from acting on the firing pin holder to overcome the lighter spring 39.

55 Upon impact of the projectile (the centrifugal pins 31 having been displaced during the rotational flight of the projectile) the plunger 26 is moved forwardly against the tension of the spring 32 through the 60 force of inertia to enable the balls 33 to be released from the guide 34. At this time the impact of the projectile will also tend to hold the guide 34 and the firing pin holder 36, under the influence of inertia and assisted 65 by the spring 39, in their forward or un-

armed position until the force of inertia is diminished sufficiently to permit the spring 35 to predominate when it will force the guide 34 and the firing pin holder 36 rearwardly until the firing pin strikes the detonator. 70

It will be apparent that the rapidity in the functioning of the delay mechanism will be proportionate to the inertia force as outlined in the premises. 75

It will also be evident that by varying the weight of the firing pin holder and the guide and the strength of the spring 35 the delay mechanism can be made to function within wide limits at a predetermined amount of 80 resistance.

The mechanism for securing instantaneous action is disposed in a fuse nose 40, threadedly secured in the fuse head 11 forwardly of the diaphragm 25. The nose is formed 85 with a cavity 40' to slidably receive a striker head 41 provided with a flanged base 41' and is counterbored to receive a spring 42 abutting the base 41'. The base of the nose 90 is formed with a central threaded passage 43 receiving a striker rod 44 whose rear portion is formed with male threads 45 while its forward portion 46 is threaded into the base 41' and riveted in place.

The forward portion of the striker head is 95 hollowed to receive a screw head 47 held against movement by a spring clip 48 and serving as a means through which the gunner may set the rod 44 in either operative or inoperative position by rotation of 100 the striker head 41.

When the rod 44 is to be set for instantaneous action, the striker head is rotated until the threaded rear portion 45 is clear of the internally threaded passage 43 when 105 it will be positioned as shown in Figure 1, projecting through the apertured diaphragm 25 into the guide 34 and in line with the stem 36 of the firing pin holder. In this position, it is free to be forced rearwardly 110 on impact to propel the firing pin into the detonator.

On discharge, the concussion will cause set back of both the firing pin and the 115 striker rod, the firing pin moving into the blind cavity 21 of the rotor until the enlarged head 37 engages the plate 23 while the striker will be stopped short of the base of the guide 34 when the flanged base 41' of the striker engages an internal annular shoulder 49 formed by the unequal bores of the fuse nose. The firing pin and the striker rod are returned to forward position respectively by the springs 39 and 42. 120

When it is desired to employ the delay mechanism, the striker rod is screwed out by rotating the striker head until the male threads are entirely disposed within the passage 43 so that upon impact the plunger will remain stationary, the striker head being 125 130

crushed. The striker rod when thus secured in unarmed position will not interfere with the independent functioning of the delay mechanism.

While in the foregoing there has been illustrated and described such combination and arrangement of elements as constitute the preferred embodiment of my invention, it is nevertheless desired to emphasize the fact 10 that interpretation of the invention should only be conclusive when made in the light of the subjoined claims.

I claim:

1. A fuse embodying a head formed with a cavity, a sleeve within the cavity, said sleeve formed with apertures, balls disposed in the apertures, a guide within the sleeve and adapted to receive a portion of the balls, a firing pin slidably disposed in the guide, 20 means for holding the firing pin, firmly against the guide, a plunger embracing the sleeve for releasably confining the balls, means carried in the guide for actuating the same to expel the balls and to move the firing pin to firing position.
2. A fuse embodying a head formed with a cavity, a sleeve within the cavity, a guide within the sleeve, means for releasably holding the guide in unarmed position, a firing element slidably disposed in the guide, a detonating element, means for holding the firing element from the detonating element during flight, and means for actuating the firing element to detonate the detonator. 30
3. A fuse embodying a head formed with a cavity, a sleeve within the cavity, a guide within the sleeve, means for releasably holding the guide in unarmed position, a firing element slidably disposed in the guide, a detonating element, and means for moving the guide and firing element to detonate the detonator. 35
4. A fuse embodying a head formed with a cavity, a sleeve within the cavity, said sleeve formed with apertures, balls disposed in the apertures, a firing mechanism within the sleeve and adapted to receive a portion of the balls, a plunger embracing the sleeve 45

for confining the balls, and centrifugally operable means for releasably holding the 50 plunger.

5. A fuse embodying a head formed with a cavity, a plunger within the cavity, said plunger formed with an internal rib, means abutting the rib for retaining the plunger 55 in unarmed position during flight, centrifugally operable releasing means engaging the end of the plunger, and a firing mechanism within the plunger releasable when the plunger is moved forwardly on impact. 60

6. A combination instantaneous and delay fuse embodying a single firing pin, a striker therefor, movable to operative position for instantaneous action, and means for limiting the movement of the firing pin and the 65 striker upon set back when the fuse is set for instantaneous action.

7. A combination instantaneous and delay fuse embodying a single firing pin, a striker therefor, movable to operative position for 70 instantaneous action, and means for returning the firing pin and striker to initial position after set back when the fuse is set for instantaneous action.

8. A combination instantaneous and delay 75 fuse embodying a common firing pin and means for limiting the movement of said pin on set back, and means for returning the pin to initial position.

9. A fuse embodying a firing pin, a striker 80 movable to operative or inoperative position for actuating said pin instantaneously upon impact and a delay mechanism for actuating said firing pin when the striker is in inoperative position. 85

10. A combination instantaneous and delay fuse embodying a firing pin and a plurality of means operable independently of each other for actuating the firing pin, one of said means being movable to inoperative 90 position.

11. A combination instantaneous and delay fuse embodying a single ignitable element and a single firing pin.

HAROLD M. BRAYTON.
